UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

LINE-LOCK MECHANISM AND MARGIN STOP.

Application filed August 25, 1921. Serial No. 495,329.

To all whom it may concern:

Be it known that I, OTTO A. HOKANSON, a citizen of the United States, residing at Woodstock, in the county of McHenry and State of Illinois, have invented certain new and useful Improvements in Line-Lock Mechanism and Margin Stops, of which the following is a specification.

This invention relates to typewriter mechanism and especially to that portion of the mechanism by which the operator is notified that the writing is approaching the end of a line and by which the operation of the typewriter is arrested at a predetermined point at the end of a line.

The invention has for its object the provision of mechanism of the class named which shall be of improved construction and operation and is exemplified in the combination and arrangement of parts shown in the accompanying drawings and described in the following specification, and it is more particularly pointed out in the appended claims.

25 In the drawings—

Fig. 1 is a vertical sectional view of a portion of a typewriter showing one embodiment of the present invention applied thereto;

30 Fig. 2 is a horizontal section substantially on line 2—2 of Fig. 1;

Fig. 3 is a front elevation of the line lock mechanism with parts in section; and

35 Fig. 4 is a perspective view of a margin stop.

In the drawings the invention is illustrated as applied to a folding typewriter having a main frame 10 and a platen carriage frame 11 which is pivotally mounted 40 on the main frame to swing into and out of operating position. The platen carriage frame 11 is provided with ways 12 having ball bearings 13 for supporting the platen carriage 14. The carriage 14 is provided 45 at each end with an upright end plate 15 on which a platen 16 is journaled. The end plates 15 have arms 17 pivoted at 18 thereon and the arms 17 are connected by a stop bar 19. One of the arms 17 extends upwardly 50 to form a finger-piece 20 by which the stop bar 19 may be swung rearwardly. The bar 19 is provided with notches 21 on its forward face and 22 on its lower face. A stop 23 is slidably mounted on the bar 19

and is formed of a piece of sheet metal bent 55 to provide a sleeve surrounding the bar and having a downwardly projecting flange 24 which carries a contact foot 25 at its lower end. A flange 26 is bent upwardly from one edge of the lower wall of the sleeve to 60 engage the notches 22 on the stop bar and a spring 27 is riveted at 28 to the under face of the top wall of the sleeve to resiliently hold the flange 26 in contact with the notches 22. When it is desired to adjust 65 the stop along the bar pressure on the upper face of the stop will free the flange 26 from the notches 22 and permit the stop to slide freely along the bar.

The head of the rivet is elongated, as 70 shown at 29, to assist the spring 27 in holding the sleeve in a raised position relative to the bar. The head of the rivet 29 is rounded to permit tilting movement of the stop sleeve to disengage the flange 26. A 75 downwardly extending finger 30 is pivoted at 31 on the flange 24 and is held against movement in one direction by engagement with the end of a slot 32 in the foot piece 25. Secured to the lower face of the platen 80 carriage frame 11 is a bracket 33 having a bell clapper 34 pivoted at 35 thereon. A bell 36 is also secured to the lower face of the platen carriage frame 11 in position to be struck by the clapper 34. A spring 37 85 normally draws the clapper toward the bell 36. A rearwardly extending arm 38 is secured to the clapper 34 and projects into the path of the contact finger 30.

As the carriage moves to the left, as 90 viewed in Fig. 2, the stop 23 will assume the broken line position in Fig. 2 and the contact finger 30 will move the arm 38 into the broken line position shown in that figure. This will retract the clapper 34 and 95 as the carriage continues to move the finger 30 will slide past the arm 38 and release the clapper permitting it to return under the tension of the spring 37 and strike the bell 36, thus warning the operator that the 100 end of the line is being approached. Further movement of the carriage to the left, as viewed in that figure, will bring the contact foot 25 into engagement with an upwardly bent portion 39 on a lever plate 105 40 pivoted at 41 on the lower face of the platen carriage frame 11. The plate 40 is provided with a slot 42 which engages a

pin 43 on the frame 11 and limits the movement of the plate by its pivot 41. The spring 37 is connected to the plate 40 and normally holds the plate in the position shown in Fig. 2. The plate 40 is provided with a rounded projection 44 which engages a bifurcated arm 45 on a bell crank 46. The bell crank 46 is pivoted at 47 on the lower face of the frame plate 11 and has a forwardly extending arm 48 provided with a hook 49 at its front end. The hook 49 is arranged to engage an upwardly extending arm 50 secured to a rocker bar 51 pivoted at 52 to the side plates of the main frame 10. The rocker bar 51 is oscillated by a universal bar 53 positioned beneath the key levers 54 and connected with the bar 51 by links 55 and arms 56 and 57. The arm 57 is rigidly connected with the bar 51, while the arm 56 is pivoted at 58 on the side of the frame 10. The two arms 56 and 57 have a pin and slot connection 59 and a spring 60 normally draws the arm 57 upwardly lifting the universal bar 53 after a key is depressed.

When the contact foot-piece 25 strikes the flange 39 on the plate 40 the hook 49 will be caused to engage the upper end of the lever 50, as shown in Fig. 1, thus locking the lever 30 in its rearmost position and holding the universal bar in its upper position. This will prevent operation of the key levers 54 and lock the printing mechanism of the typewriter.

If it is desired to write in the margin past the position at which the line lock operates, the finger-piece 20 may be depressed which will swing the bar 19 outwardly, thus freeing the flange 39 from the foot-piece 25. As soon as these parts are moved out of contact with one another the spring 37 will draw the flange 39 to the right, as viewed in Fig. 2, and bring it opposite the inner edge of the foot-piece 25. If the finger-piece 20 is now released the inner edge of the foot-piece 25 will rest against the outer face of the flange 39 and the carriage will be free to move farther to the left. The movement of the lever plate 40 by the spring 37 will release the hook 49 from the lever 50 and free the key levers 54 from the line locking mechanism. The operation of the typewriter may be resumed until the carriage comes to the limit of its movement.

When it is desired to return the carriage it is only necessary to move it to the left along the ways 12. It will be noted that the foot-piece 25 is provided on its right-hand edge with a beveled contact portion 61 which will engage the flange 39 and swing the bar 19 outwardly to permit the foot-piece to pass the flange. When the finger 30 engages the arm 34 the finger will turn about its pivot 31 so that the movement of the carriage will not be interfered with. When the platen

carriage frame is moved upwardly about its pivot for folding the line lock mechanism will fold with the frame and when it is returned to operating position the hook 49 will resume its place adjacent the lever 50 so that it will be in position to perform its locking function when operation of the typewriter is resumed.

The movement of the carriage to the right is limited by a stop 23' similar to 23, but having its beveled surface and contact shoulder in reverse position from that of stop 23 so that the stop may be shifted by the finger-piece 20 for writing in the left-hand margin and will return past the contact member 39 which engages with the beveled portion of the stop foot 25 when the carriage is again fed to the left and throws the stop and bar outwardly, as in the case of stop 23.

I claim:—

1. In a typewriter, a universal bar, an oscillatory member operated by said universal bar, a lever having a hook thereon for engaging said oscillatory member to prevent operation of said universal bar, a platen carriage movable on said typewriter, and means for actuating said lever to lock said oscillatory member when said platen carriage approaches the end of its travel.

2. In a typewriter, a main frame having key levers thereon, an upwardly projecting arm on said main frame and arranged to be oscillated by said key levers, a supplemental frame movably mounted on said main frame and having a platen carriage movable transversely thereof, and a lock carried by said supplemental frame and arranged to engage said upwardly projecting arm on said main frame to hold said arm against operation when said carriage approaches the end of its travel.

3. In a typewriter, a supporting frame, a platen carriage arranged to travel transversely thereof, a stop bar pivotally mounted on said platen carriage to swing in a direction transversely of said bar, a stop adjustably mounted on said bar, key levers for said typewriter, a catch on said supporting frame for locking said key levers against operation, and means connected with said catch and arranged to be engaged by said stop to cause said catch to lock said key levers against operation when said platen carriage approaches the end of its travel.

4. In a typewriter, a supporting frame having a platen carriage movable transversely thereof, a stop bar movably supported on said carriage, a stop arranged on said bar, said stop comprising a sheet metal sleeve having a fixed tooth thereon for engaging notches in said bar, a spring for holding said tooth in contact with said notches, and a foot-piece projecting downwardly from said sleeve and having a contact face in one side thereof and a beveled face at the opposite side thereof

- for swinging said stop bar upon said carriage to permit movement of said carriage in one direction without interference by said stop.
5. In a typewriter, a platen carriage, a stop bar movably mounted on said carriage and having notches therein, a stop slidably mounted on said stop bar, said stop having a tooth-piece thereon for engaging said notches, a spring for yieldingly holding said tooth-piece in contact with a notch on said bar, a pivoted contact finger on said stop, means for holding said finger against movement in one direction while permitting movement thereof relative to said stop in the opposite direction, and a contact foot on said stop having a stop face at one side thereof and a beveled face at the opposite side thereof for moving said stop bar to permit travel of said carriage in one direction.
- 10 6. In a typewriter, a supporting frame, a platen carriage arranged to travel along said frame, a stop bar on said carriage, a stop adjustably mounted on said bar, an alarm device on said supporting frame, a contact member on said stop arranged to actuate said alarm device when said carriage moves in one direction but permitting free movement of said carriage in the opposite direction without affecting the alarm device, a second contact member on said stop, line lock mechanism on said supporting frame engaged by said second contact member subsequent to the operation of said alarm device, manually operated means for swinging said stop bar to permit movement of said carriage after the operation of said line lock mechanism to continue the writing operation in the same line, and means on said stop for moving said stop bar on said platen carriage to permit return movement of said carriage without interference by said line lock mechanism.
- 15 7. In a compactible typewriter, a main frame, key levers on said main frame, a universal bar operated by said key levers, an oscillatory member actuated by said universal bar, a platen carriage frame foldably mounted on said main frame, a latch on said platen carriage frame movable into and out of position to cooperate with said oscillatory member when said platen carriage frame is folded, a platen carriage arranged to travel transversely of said typewriter on said platen carriage frame, a stop bar pivotally mounted on said platen carriage frame, a finger-piece for moving said stop bar, a stop on said bar having contact devices thereon, an alarm on said platen carriage frame and having actuating means projecting in the path of one of said contact members on said stop so that said alarm is operated by the movement of said carriage as it approaches the end of a line, and a lever having a contact member thereon projecting into the path of the other contact member
- 20 on said stop, said lever being arranged to actuate said latch to lock said universal bar and key levers against operation subsequent to the operation of said alarm device, said finger-piece being movable to shift said stop bar and free said latch to permit further writing in the same line subsequent to the operation of said latch.
- 25 8. In a typewriter, a main frame having key levers and a universal bar carried thereby, a supplemental frame pivotally mounted on said main frame, a platen carriage movable on said supplemental frame, a pair of arms each having one end pivotally mounted on said platen carriage, a stop bar connecting the other ends of said arms, a finger lever connected with one of said arms for moving said stop bar bodily in a direction transverse to the length thereof, a stop adjustably mounted on said stop bar, a signal lever pivoted on said supplemental frame in position to engage said stop as said carriage moves along said supplemental frame, a bell crank lever pivotally mounted on said supplemental frame having one end thereof arranged in the path of said stop in position to be engaged thereby subsequent to the engagement of said stop and signal lever, a catch mounted on said supplemental frame and actuated by said bell crank lever, a movable member connected with said universal bar and arranged in position to be engaged by said catch when said bell crank lever is actuated by said stop, and a common spring connected to said signal lever and bell crank lever to hold said levers in position to be engaged by said stop.
- 30 9. In a typewriter, a main frame having key levers and a universal bar mounted thereon, an oscillatory member connected with said universal bar and actuated by said key levers, a supplemental frame pivotally connected with said main frame and having a catch pivotally mounted thereon in position to engage said oscillatory member when said supplemental frame is in operative position to hold said oscillatory member and universal bar against operation, a bell crank lever pivotally mounted on said supplemental frame and having pivotal connection with said catch, a platen carriage mounted to move along said supplemental frame, a stop bar carried by said platen carriage, an adjustable stop on said stop bar arranged to engage said bell crank lever and actuate said catch to engage said oscillatory member when said carriage reaches a predetermined position in its travel, and means for shifting said stop bar in a direction transverse to the length thereof to free said stop from said bell crank lever.
- 35 10. In testimony whereof I have signed my name to this specification on this 22nd day of August, A. D. 1921.
- 40 OTTO A. HOKANSON.
